ASH TRAY

John H. Dawson, 359 Congressional Lane, Rockville, Md.

Filed July 20, 1962, Ser. No. 70,998

Term of patent 14 years

(Cl. D85—2)

FIG. 1.

FIG. 2.

I claim:

The ornamental design for an ash tray, substantially as shown.
